UNITED STATES PATENT OFFICE.

VERN SLATER AND LEONIDAS D. WEST, OF DENVER, COLORADO, ASSIGNEES, BY MESNE
ASSIGNMENTS, TO VERN SLATER, OF DENVER, COLORADO.

FUME-DISSEMINATOR.

1,273,682.

Specification of Letters Patent. Patented July 23, 1918.

Application filed June 9, 1916. Serial No. 102,687.

To all whom it may concern:

Be it known that we, VERN SLATER and LEONIDAS D. WEST, citizens of the United States, residing at Denver, in the county of Denver and State of Colorado, have invented certain new and useful Improvements in Fume-Disseminators; and we do declare the following to be a full, clear, and exact description of the invention, such as will enable others skilled in the art to which it appertains to make and use the same.

Our invention relates to improvements in attachments for treating a forced flow of air with a suitable liquid agency, and diffusing the same laden with moisture taken up from said treating agency, the object thereof being to provide a comparatively simple and inexpensive device of this class which will be highly efficient and adaptable to a wide range of uses.

With this general object in view, the invention resides in certain novel features of construction and in unique combinations of parts to be hereinafter fully described and claimed, the descriptive matter being supplemented by the accompanying drawing which constitutes a part of this application, and in which:

30 Figure 1, is a view, in side elevation and partly in section, of an air delivery casing, showing our invention applied thereto; Fig. 2, is an enlarged vertical sectional view, taken longitudinally through the improved attachments; Fig. 3, is a vertical sectional view, taken transversely in the plane of the line 3—3 of Fig. 2; and Fig. 4, is an enlarged longitudinal sectional view through the detached absorbent moistening element 40 and its metallic gauze support.

In specifically describing the structure shown in the drawing similar characters will be employed to designate corresponding parts throughout the several views, and reference will be herein made to the numerous elements by their respective indices. To this end the numeral 1 designates a suitable base from which a casing 2 rises, said base having mounted thereon a motor 3 which

50 drives a rotary centrifugally delivering fan 4 for drawing air into the casing 2 at the upper end thereof and for discharging such air through an outlet nipple 5, to which is suitably connected the larger end of a 55 frusto-cone-shaped nozzle 6, the outer smaller

end of which may be coupled up, when desired, with a suitable flexible tube, as indicated in dotted lines in Fig. 1.

Mounted in the nozzle 6 and held therein by frictional engagement therewith, is an 60 absorbent member 8 which is adapted to be saturated with the treating liquid used, said member being composed of a hollow frusto-cone-shaped body 9 formed of wire gauze, and a covering 10 of any suitable 65 absorbent material such as cloth or felt, open mesh goods being preferably employed in constructing said covering. The wire gauze 9 serves not only to retain the pad or absorbent covering 10 in proper position 70 within the nozzle 6, but said gauze is resili- 75 ent to a high degree and thus the entire member 8 will be held in yielding frictional contact with the interior surface of said nozzle. This permits removal of said mem- 75 ber 8 when necessary but it will otherwise be effectively held in operative position.

For supplying the liquid to the member 8, a reservoir 11 is provided, such reservoir being preferably in the form of an inverted 80 cup whose lower end is closed by a screw cap 12 to which is secured one end of a valve casing 13, the other end of said cas- 85 ing being threaded in a boss on the upper side of the nozzle 6. The bore through the 85 casing 13 is preferably of rather small di- 90 ameter and the passage of liquid there- through may be accurately controlled by means of a needle valve 14. For permitting air to enter the reservoir 11, thus allowing 90 the liquid to escape therefrom, an upright tube 15 preferably rises through the cap 12 as shown. A screw cap 16 is shown applied to the projecting lower end of tube 15 and if the threaded connection between the two 95 be sufficiently loose, loosening of said cap will permit the necessary amount of air to enter the reservoir. Under other conditions, however, it will be necessary to remove the cap 16, but it may be applied and tightened 100 whenever necessary to prevent the entrance of air into the reservoir, thus insuring that the contents of the latter be not unneces- sarily evaporated.

In filling the reservoir 11, the nozzle 6 105 will be detached from the nipple 5 and the entire device will be inverted to dispose the open end of said reservoir upwardly. The cap may now be easily unthreaded from the reservoir 11 to permit filling thereof and 110

said cap will be again applied, after which the device will be returned to its normal position with the reservoir uppermost, and will thus be in condition for further operation.

Obviously the liquid from the reservoir will be supplied by the absorbent member 8 in greater or less quantity according to the manner in which the valve 14 is set, said 10 valve being also capable of cutting off the entire supply when required, and a current of air being discharged from the casing 2, in passing through the nipple 5 and nozzle 6, it will become laden with moisture exuded 15 from the liquid with which the member 8 is saturated.

In spite of utmost cleanliness and sanitation, the atmosphere in rooms in which a number of persons are assembled has a close 20 oppressive odor, and while not so perceptible to the constant occupant, it is quite unpleasant to a new arrival from the fresh air. Such disagreeable conditions may be readily overcome by impregnating the air 25 in the room with a pleasant fragrance if perfume be employed in the reservoir 11. The arrangement is also of great advantage in supplying medicated air in sick rooms and in perfuming or deodorizing the air 30 in such rooms, and while we have termed our attachment a fume disseminator, in the latter uses just mentioned it will be apparent that fumes, in their technical sense of noxious gases, are not generated, as would 35 be the case in fumigation proper.

From the foregoing, taken in connection with the accompanying drawing, the construction, uses and advantages of the invention will be readily understood, but in conclusion we will state that although we have shown and described certain specific details for illustrative purposes, numerous changes may be made within the scope of the invention as claimed without sacrificing the main 45 characteristics thereof.

We claim:

1. In appliances of the character set forth, the combination with a nozzle, having a hollow tapering body portion, adapted to be 50 connected with a source of forced air sup-

ply, of a similarly tapering absorbent element dimensioned to fit therein, means for holding said absorbent element in wedged relation thereto, and means for delivering a suitable liquid to said absorbent element 55 for maintaining the latter saturated therewith, substantially as described.

2. In appliances of the character set forth, the combination with a nozzle, having a hollow tapering body portion, adapted to be 60 connected with a source of forced air supply, of an absorbent member formed and dimensioned to snugly fit within said nozzle, said member comprising a hollow body of wire gauze provided with a covering of absorbent material held in yielding frictional contact with the interior tapering surface of said nozzle by the resiliency of the wire gauze, a valved conduit element carried by 65 said nozzle and communicating with said absorbent member therein, and a reservoir supplying said conduit with a suitable saturating liquid for said absorbent member, substantially as described.

3. In appliances of the character set forth, the combination with a portable casing having an air inlet and an air outlet together with an associated rotary blower, of a nozzle, provided with a hollow tapering body portion, adapted to be connected with said 80 air outlet, an air moistening element formed and dimensioned to snugly fit within said nozzle, said element comprising a hollow tapered foraminous support enveloped with a covering of absorbent material, a valve 85 controlled feed conduit leading to said moistening element, through an aperture in said nozzle body, and a reservoir, carried by and communicating with said valved conduit element, for supplying a controlled flow of 90 a suitable liquid to said absorbent material, substantially as described.

In testimony whereof we have hereunto set our hands in the presence of two subscribing witnesses.

VERN SLATER.
LEONIDAS D. WEST.
